UNITED STATES PATENT OFFICE.

GEORGE W. PUGH, OF PHILADELPHIA, PENNSYLVANIA, ASSIGNOR TO THE HORNER BROTHERS, OF SAME PLACE.

DESIGN FOR A CARPET.

SPECIFICATION forming part of Design No. 12,783, dated February 21, 1882.

Application filed January 11, 1882. Term of patent 3½ years.

To all whom it may concern:

Be it known that I, GEORGE W. PUGH, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim as my invention—
The design for a carpet, as shown.

GEO. W. PUGH.

Witnesses:

JOHN T. THOMPSON,
THOMAS ONSLOW.
